CLAIM

The ornamental design for a push lock hanger for shallow channel metal frame, substantially as shown and described.

DESCRIPTION

FIG. 1 is a perspective view showing the front, left side and top of the push lock hanger for shallow channel metal frame;

FIG. 2 is a perspective view showing the rear, right side and bottom of the FIG. 1 push lock hanger for shallow channel metal frame; and

FIG. 3 is a side view of the FIG. 1 hanger inserted into a shallow channel metal frame shown in broken lines.
